UNITED STATES PATENT OFFICE.

CHARLES COLAHAN, OF CHICAGO, ILLINOIS.

GRAIN-BINDER.

SPECIFICATION forming part of Letters Patent No. 677,943, dated July 9, 1901.

Application filed March 15, 1901. Serial No. 51,344. (No model.)

To all whom it may concern:

Be it known that I, CHARLES COLAHAN, a citizen of the United States, and a resident of Chicago, in the county of Cook and State of Illinois, have invented certain new and useful Improvements in Grain-Binders, of which the following is a specification, reference being had to the accompanying drawings, forming a part thereof.

10 My invention has relation to grain-binders and to that part pertaining to the function of tying the knot in the band that secures the bundle, and more particularly to that form of knotter that stands in its normal position 15 with the bill pointing outwardly as the bundle is discharged and the band is placed around the succeeding bundle.

My invention has for its object the economizing of band material and removing much 20 of the strain upon the twine during the compressing and binding operation and also places the band closely around the bundle and provides slack cord for the formation of the loop. This permits the use of a small twine, 25 which is usually sold by the pound and is often much larger and heavier than is required to hold the bundle, as the strain upon the twine in forming the knot is usually quite severe in the ordinary knotters.

30 My present invention consists in improvements upon my former patents, No. 425,565, dated April 15, 1890, and No. 476,519, dated June 7, 1892, and is applicable to grain-binders of the modern form having the vertical 35 revolving knotter-shaft with the horizontal looper, with a vertically-vibrating pivoted jaw, known as the "Appleby" type, and that stands over the breastplate or near the angularly outwardly curved corner of the open slot 40 of the breastplate, through which the binder-arm passes in placing the cord around the bundle and over the tying-bill to the cord-holder and in which it is important that a support or stop be provided across the slot in 45 the breastplate for the cord strands at the inner side of the knotter-jaw as the tying-bill stands with its jaws pointing outwardly in the direction of the length of the slot in the breastplate, as shown in patent to Prid- 50 more, No. 481,244, dated August 23, 1892.

In my former patents I have shown a finger secured to the tying-bill and revolving

therewith, and my present invention provides an improved outsetting cord-supporting finger, which is secured to the rear of the 55 pivoted knotter-jaw and formed integral therewith, which has advantages over my former invention, as it enables me to bring the cord-supporting finger down nearer the bundle and across the open slot in the 60 breastplate on a plane with the knotter-jaws, so that it may contact with the cord-guiding flange of the breastplate on the opposite side of the slot at the same point that the tier-bill will pass in its revolution, and 65 when the cord slips from the cord-supporting finger and is received by the tier-bill it furnishes slack cord for the formation of the loop, and as the bill continues its revolution and the jaw opens to seize the outer ends 70 of strands from the cord-holder the finger will rise over said strands of cord, which will enter the open jaws that close firmly upon the same, and the loop is slipped over the same toward the bundle, and the ends, held 75 by the knotter-jaw, pass within the loop in the usual manner as the cord is stripped from the knotter by the discharging bundle, thus securely forming the knot. I also provide a 80 depression at the inner side of the knotter-jaw in the outward curvature of the upper surface of the breastplate, which serves to retain the outer strand of cord that is around the outer side of the bundle at the moment the knotter-jaw opens to seize the ends of the 85 cord from the cord-holder and prevents the loop from escaping outwardly over the curved surface of the breastplate and being drawn off the tier-bill just before it closes its open jaw. It is important that this depression be 90 very slight and upon the upper surface only, as its function in connection with the opening of the jaw would otherwise interfere with the formation of the knot or hold back the cord, which should pass from it on the final 95 revolving movement of the knotter and be free when the bundle is ejected. This depression does not extend to the lower surface of the slot in the breastplate that in its line and curvature is in a plane parallel with 100 the under surface of the breastplate.

Any vertical or horizontal cord-holder may be employed, and I have not shown that part of the binder, but have illustrated the breast-

plate and its cord-guides, which are cast in one piece, and also show fully the various positions of the knotter in its operation of receiving the cord from the binder-arm (the latter not shown) and forming the knot as used in my invention.

In the drawings, Figure 1 is a top plan view of that portion of the breastplate showing my invention therein. Fig. 2 is a vertical section of the same on line 2 of Fig. 1. Fig. 3 is a top plan view showing the breastplate the same as in Fig. 1 and the knotter-bill and its cord-supporting finger in the normal position as the cord has been placed thereon, the bundle (not shown) beneath the breastplate being encircled by the cord and all parts in position for the operation of the knotter. Fig. 4 is a view of the same when the knotter has made its initial movement and the cord has slipped from the cord-supporting finger upon the knotter-jaws. Fig. 5 shows the jaw in its continuous movement as the loop is being formed and at a point when the knotter-jaw opens, as shown in the vertical sectional view, Fig. 7, the cord-supporting finger having risen with the opening of the jaw and passed over the strands of cord which are still retained by the cord-holder and will now pass into and be seized by the open jaw of the knotter and firmly held, as shown in Fig. 6, wherein the knotter has performed one complete revolution, and at which instant the cord is cut and the loop is slipped therefrom and over the ends held by the jaw as the bundle is discharged, leaving the knotter in its normal position with the cord-finger extending over the slot, as shown in Fig. 3, and ready for another revolution.

In the drawings, A represents the breast-plate; a, the depression in the upper surface of the breastplate; B, the cord-guiding flange; b, a notch therein that serves as a seat or way for the cord-supporting finger and revolving knotter-jaw.

C is the rigid lower knotter-jaw; c, the projecting flange common to this form of jaw; D, the pivoted jaw; D', the cord-supporting finger formed integral therewith.

My invention offers great advantage in the construction and operation of grain-binders, and I have demonstrated that it has many valuable features not shown in former devices, as it simplifies the construction and insures a direct action and coöperation of all the parts affected in this work, securing a certainty of desired results and dispenses with the necessity of experts in the field, while at the same time the power required to operate it is much less than usual and the cord is drawn tighter around the bundle.

Having thus described my invention, what

I claim, and desire to secure by Letters Patent, is—

1. The combination of the knotter of the Ap-pleby type and its cord-supporting outsetting finger D' formed integral with the pivoted jaw D to raise the cord substantially as shown and described.

2. The combination with the cord-knotter, which in its normal position stops with its jaws pointing outwardly, of a breastplate having the open binder-arm slot extending to a point beyond the knotter, the knotter being provided with a cord-supporting finger formed integral with its vibrating jaw, which finger moves on a plane parallel with the plane of movement of the knotter-jaw, and supports the cord in the initial revolution of the bill, rising with the opening of the movable jaw to pass over the strands as they enter between the jaws to be grasped and pulled through the loop substantially as shown and described.

3. The combination with the tying-bill, which in its normal position stands with its jaws pointing outwardly, as the knot is stripped therefrom, of the open angularly-slotted breastplate provided with a depression on its upper surface only to momentarily arrest the cord while the jaw opens to seize the outer ends of the strand, the under side of the breastplate being in the line of the direction of the outgoing bundle, the said notch being located at the reentrant angle of the slot, thereby admitting the free discharge of the bundle substantially as shown and described.

4. In combination with the knotter revolving over the breastplate, the jaws of which open to receive the outer ends of the strands of cord when trending in an outward direction, of the open angularly-slotted breast-plate provided with a depression in the re-entrant angle of the outwardly-curved slot on its upper surface only to receive therein the strand of cord that is around the outer side of the bundle beneath the breastplate, and prevent its escape as the jaw continues to revolve and opens to grasp the outer ends of the strand of cord that is drawn through the loop to complete the knot substantially as shown and described.

5. In combination, as hereinbefore set forth, with the knotter, of the breastplate, A, having the cord-guide B and its notch b upon one side of the open slot, and the depression a upon the upper surface, on the opposite side, formed integral therewith substantially as shown and described.

CHARLES COLAHAN.
